UNITED STATES PATENT OFFICE

CHARLES WESLEY JONES, OF GLEN RIDGE, NEW JERSEY, ASSIGNOR TO SONS-CUNNINGHAM REED & RATTAN CO., INC., OF NEW YORK, N. Y., A CORPORATION OF NEW YORK

DESIGN FOR A FRAME OF A CHAIR OR SETTEE

Application filed November 7, 1929. Serial No. 33,367. Term of patent 7 years.

To all whom it may concern:

Be it known that I, CHARLES WESLEY JONES, a citizen of the United States, residing at Glen Ridge, in the county of Essex and State of New Jersey, have invented a new, original, and ornamental Design for the frame of a Chair or Settee, of which the following is a specification, reference being had to the accompanying drawing, forming part thereof.

The drawing is a plan view of a chair frame embodying my design, it being understood that the design, shown in full lines, is repeated at the other end of the chair as indicated by dotted lines. A side view of the chair shown, viewing the arm of the chair

edgewise, would show of the chair arm merely one side of the strip forming one side of the main loop of the arm.

The dominant feature of the design is in the arm comprising as viewed from above an elongated loop having a rounded front end and tapered toward the rear and a series of smaller figure eight loops within the main loop.

I claim:

The ornamental design for the frame of a chair or settee, as shown and described.

In witness whereof, I have hereunto set my hand.

CHARLES WESLEY JONES.
